UNITED STATES PATENT OFFICE.

HARRY HAMMOND BOWERMAN, OF LORELEY, MARYLAND.

CORN-HARVESTER.

SPECIFICATION forming part of Letters Patent No. 712,086, dated October 28, 1902.

Application filed January 18, 1900. Serial No. 1,823. (No model.)

To all whom it may concern:

Be it known that I, HARRY HAMMOND BOWERMAN, a citizen of the United States of America, residing at Loreley, in the county of Baltimore and State of Maryland, have invented 5 certain new and useful Improvements in Corn-Harvesters, of which the following is a specification.

This invention relates to corn-harvesters, 10 and more particularly to that class adapted to cut corn and to drop the same in piles at equal distances apart.

The object of my invention is to provide a 15 corn-harvester which is so constructed as to cut two rows of corn at a time and to drop the same between the rows at equal intervals apart.

Another object of my invention is to provide a corn-harvester in which the working 20 parts are unique and compact, the friction being reduced to a minimum, thus affording such an easy movement that it requires but one horse to draw the machine.

With these objects in view my invention 25 consists in certain details of construction, arrangement, and combination of parts, all of which will be described hereinafter.

The novel features of the invention are 30 pointed out in the appended claims, which are intended to accord in their terms, spirit, and meaning with the prior state of the art and the existing law.

In the drawings forming a part of this specification, Figure 1 is a top plan view. Fig. 2 35 is a side elevation with one of the wheels removed. Fig. 3 illustrates the trough. Fig. 4 is a detail view of the cutting portion of the machine. Fig. 5 is a side elevation of Fig. 4, showing the parts detached and the gearing 40 removed.

Referring by letters to the drawings, A represents the wheels connected by axle B, which is adapted to support the machinery. Mounted in the center of the axle is the frame, comprising the two beams C C, braced together, the forward ends of which are supported by a wheel D and are adapted to receive a cross-bar for the attachment of the shafts. Journaled upon the braces between the beams are 45 two shafts E E, the forward ends of which are provided with cogs a a, adapted to mesh with semicircular cogs b b upon opposite sides

of the lever F. It will thus be seen that the semicircular cogs b b, which are intermediate the cogs a a and in engagement therewith, 55 will when operated by the lever F cause the rack to be dumped or set according to the direction in which the lever is thrown. The central portions of the shafts are bent at right angles in opposite directions and are provided with lugs c c, which engage the rear ends of the beams. The shafts are then bent down at right angles and then bent again at right angles, with their free ends projecting rearwardly parallel with respect to each other 60 and flattened, as shown at G, the flattened portion being provided with rods d for the reception of the stalks.

Mounted upon each side of the frame upon the axle is the cutting portion of the machine 70 and the apparatus for conveying the stalk to the rack.

The cutter-frame comprises a block H, having a longitudinal slot e, adapted to receive the plate I, which is pivoted therein in order 75 to be moved to the right or left, according to the position of the stalk, which is engaged by the notched ends thereof, the same being normally held in the forward position by the coiled springs f f. This plate is also provided 80 with longitudinal slots g and h, the slot g having a recess i. The forward end of the plate is curved up and provided with a series of notches J, adapted to straddle the stalks and to guide the plate either to the right or 85 left, as the position of the stalk may require, and to hold the stalks in contact with the knives.

Journaled in the slot g at the point where the plate I is pivoted is a cog K, having a 90 bevel-cog L upon the top thereof adapted to mesh with a bevel-cog M, keyed to the axle and working through the notch j. The cog K is adapted to engage and drive the cog N, which is also journaled in the slot g on a 95 shaft which carries a beveled cog O upon the top of the plate. The cog N engages and drives the cog P, which operates the circular knife Q, journaled in the slot h.

Mounted upon the plate I is the apparatus 100 for conveying the stalk to the rack. It consists of two uprights R R, having a trough S intermediate thereof at the base, which supports the butt of the stalk after it has left

the knife. This trough is provided with a spring-actuated arm *t*, which is secured in the side of the trough, also with a trip-arm *u*, which is pivoted in the side of the trough 5 and is held normally across the trough by a coiled spring. It will thus be seen that as the stalk is carried through the trough its lower end will be brought in contact with the spring-actuated arm, which serves as a guide.

10 The object of having this arm spring-actuated is to prevent the stalks from becoming jammed, and thereby stopping the passage-way, also to hold the stalks sufficiently tight to cause them to fall slowly when tripped by

15 the trip-bar *u*, which is provided with a coiled spring adapted to control the trip and to make its operation more gradual. The uprights are provided with upper and lower guide-rails *TT* and *UU*. Each of the upper 20 guide-rails has rearwardly-extending curved rods for guiding the stalk into the rack.

Mounted upon each of the upper guide-rails are pulleys *k*, connected by belts *l*, which are provided with lugs *m*, adapted to grasp 25 the stalk, force it in contact with the knife, and then carry it back to the rack. These pulleys and belts are operated by a shaft *V*, journaled on the outer guide-rails and provided with a bevel-cog *n*, adapted to mesh 30 with and to be driven by the beveled cog *O*. This shaft is provided with pulleys *o*, which are connected by belts *p* to the pulleys *q*, mounted beneath the outer guide-rails on the same shaft that supports the pulleys *k* in the 35 forward ends of the rails.

The cutter-frame of the machine and the conveyers are raised or lowered to the desired position by the levers *W W*, connected by belts *r r*, which pass over guides *s s*, mounted 40 on the frame, to the arm *X*, secured to the plate *H* or formed as a part thereof.

It will be obvious that various changes in the form, proportion, and minor details of construction may be resorted to without departing from the spirit or sacrificing any of 45 the advantages of the invention.

Having thus described my invention, what I claim as new, and desire to secure by Letters Patent, is—

50 1. In a corn-harvester, the combination of two wheels keyed to an axle, of a frame supported by the axle and a colter-wheel, of two shafts journaled on the said frame, the said shafts having cogs on their forward ends

meshing with semicircular cogs on a lever, of 55 the rear ends of the shafts forming a rack, of cutter-frames and conveyers mounted upon the axle on each side of the first-mentioned frame, and levers for raising or lowering the said cutter-frames, substantially as shown and 60 described.

2. In a corn-harvester, a combination of two wheels keyed to an axle, a frame supported by the axle and a colter-wheel, shafts journaled upon the said frame, said shafts carrying racks and means for operating the same, cutter-frames mounted upon the axle one upon each side of the first-mentioned frame, the said cutter-frames consisting of blocks each having a slot therein, plates pivoted in the slots, springs normally holding the plates in line with the said blocks, the slots in the plates registering with the slots in the blocks, notches in the free ends of the plates, knives working in connection with the 75 said notches and a series of gear-wheels journaled in the said slots adapted to be driven by gears upon the axle, and to drive the knife, and conveyers mounted upon the said cutter-frames, substantially as shown and described. 80

3. In a corn-harvester, the combination of two wheels keyed to an axle, a frame supported by the said axle and a colter-wheel, shafts journaled upon the said frame said shafts carrying racks and means for operating the same, cutter-frames mounted upon the axle, one upon each side of the first-mentioned frame, the said cutter-frames each consisting of two parts pivoted together, a train of gearing and a knife mounted in each cutter-frame, conveyers mounted upon the said cutter-frame the said conveyers comprising troughs having uprights upon each side thereof, supporting guide-rails, pulleys mounted upon each end of the said guide-rails and connected by belts having lugs thereon, means for driving the pulleys, automatic trips arranged within the troughs, and curved guide-rods upon the rear ends of the guide-rails, substantially as shown and for the purpose 90 set forth.

In testimony that I claim the foregoing as my own I have hereunto affixed my signature in the presence of two witnesses.

HARRY HAMMOND BOWERMAN.
